UNITED STATES PATENT OFFICE.

ALBURTO BEMENT, OF CHICAGO, ILLINOIS.

HUMIDIFYING DEVICE.

1,182,624.

Specification of Letters Patent.

Patented May 9, 1916.

Application filed February 2, 1914. Serial No. 816,047.

To all whom it may concern:

Be it known that I, ALBURTO BEMENT, a citizen of the United States, residing at Chicago, in the county of Cook and State of Illinois, have invented certain new and useful Improvements in Humidifying Devices, of which the following is a specification.

My invention relates to a device for humidifying the atmosphere of an apartment by introducing steam into the same from a steam radiator, steam pipe, or other source of supply of steam.

One of the principal objects of the invention is to provide a device of this type which will operate in perfect silence.

Another object is to provide an arrangement for maintaining the temperature of the steam passing through the device above the point of condensation, thereby obviating the danger of blowing water into the room to the injury of carpets and furniture.

A further object of the invention is to provide a humidifying device which will be compact and simple in its construction, inconspicuous in appearance, cheap to manufacture, and readily attachable to an ordinary steam radiator.

The invention has for further objects such other new and improved devices, arrangements and constructions relating to humidifying devices as will be hereinafter described and claimed.

The invention is illustrated, in a preferred embodiment, in the accompanying drawing, wherein—

Figure 1 is a side elevation of a steam radiator with the humidifying device of my invention attached thereto; Fig. 2, a longitudinal sectional view through the device and a portion of one unit of the radiator; Fig. 3, a sectional plan on line 3—3 of Fig. 2; Fig. 4 is a sectional plan on line 4—4 of Fig. 2.

Like characters of reference designate like parts in the several figures of the drawing.

Referring to the drawing, 10 designates a fitting preferably formed with a nipple 11 by means of which it may be attached to the radiator, designated 12 in the drawing, or to some other element containing a supply of steam. Secured to the fitting 10 is an outer, preferably cylindrical, casing 13 and an inner, similarly formed, casing 14. The fitting is formed with a web 15 providing

a steam port 16 opening into the chamber 17 within the inner casing 14. The web 15 has an interior threading for the threaded stem of a valve 18 which closes against a conical seat 19. The stem of the valve is preferably packed by a packing 20 held in place by the bonnet 21. Steam is admitted to the chamber 17, when valve 18 is open, through a pipe 22 tapped into the web 15 and preferably extending through the nipple 11 into the middle of the radiator unit to which the device is attached so as to take the steam from the radiator at the place where it will be hottest and driest and at a point remote from the opening in the nipple 11 so that water of condensation outflowing through the nipple will not be drawn back into the device. The outer and inner casings 13 and 14 are provided with heads 23, 24 respectively, having central openings into which is fitted a short tube 25 through which the steam from chamber 17 is discharged directly to the atmosphere without coming into contact with any part or element likely to cause condensation. The head 23 closes the space 26 between the inner and outer casings providing a steam jacket which completely surrounds the chamber 17 through which the steam passes from the radiator to the atmosphere. Preferably the wall of the outer casing extends a short distance beyond the head 23 so as to provide a space 27, in which any water that may issue with the steam from the discharge pipe 25 will be collected and held until it is evaporated. A ring 28 stiffens the structure at the end and provides means for preventing water from dripping out if the device be disposed in horizontal position instead of in the vertical position shown in the drawings.

Arranged within the chamber 17 is a body, preferably cylindrical in form, through which the steam is compelled to pass before it can reach the outlet pipe 25. This body, which is permeable to steam but in small quantities relative to its area, acts as a silencer making the operation of the device perfectly noiseless. It is made up preferably of hollow cylindrical elements 29, 30, of fine wire mesh, arranged one within the other and between them a sheet or film 31 of asbestos or other similar material of a texture permitting the steam to pass through it in small quantities per unit area.

The steam in passing through the silencer is wire drawn and hence superheated so that it issues from the device to the atmosphere of the room in perfectly dry condition.

5 In order to allow the escape of air from the steam jacket space 26 when steam is first turned on in the radiator, the device is preferably provided with a small pipe 32 which 10 extends from the jacket space through the web 15 into steam port 16. Inasmuch as, with valve 18 open, steam from the jacket will pass through pipe 32, as soon as the jacket is filled it will be possible to omit 15 entirely the pipe 22 and depend upon steam from the jacket for the supply to chamber 17. I prefer to employ the pipe 22 as this insures drier steam. The purpose of the steam jacket contained in space 26 is to 20 prevent condensation of the steam in chamber 17 which, if it occurred to any considerable extent, would cause the device to sputter, diminish the volume of steam entering the room by wetting the silencing body 25 and making it less permeable, besides possibly causing a blowing of water into the room. The body of steam in the jacket keeps all of the parts with which the steam discharging into the room comes into contact at a relatively high temperature. Preferably the device is constructed as shown so 30 that the jacket space is always open to the radiator whether valve 18 is opened or closed so that if the outflow of steam to the 35 room is shut off for a time when the device is re-opened the steam comes into contact with surfaces which are hot.

While I have described my invention in a preferred embodiment, modifications 40 might readily be devised without departure from the principles of the invention. Therefore I do not wish to be understood as limiting the invention to the particular constructions, arrangements and devices shown 45 and described except so far as the same are made specifically limitations in certain of the claims herein. However, I do not make any generic claim herein to the constructions, arrangements of parts or combinations 50 which are common to the particular form of device shown in this application and to both of the forms of the invention shown in my co-pending application Serial No. 32,591, filed June 7, 1915; such claims being placed 55 in said later filed case for the purpose of maintaining a proper line of division between the two applications.

I do not claim broadly herein the arrangement of the silencing element entirely within 60 the device so that it and the discharge pipe therefrom will be kept hot by the steam jacket. Nor do I claim broadly herein the provision of a steam inlet pipe separate from and terminating in a point remote 65 from the passageway through which water

of condensation runs back into the radiator. These combinations are claimed in my co-pending application above referred to.

I claim:

1. In a humidifying device the combination with a fitting having a nipple for attaching it to a radiator or the like, and formed with a steam port, of a hollow element secured to said fitting into which said steam port discharges, a hollow silencing body permeable to steam which is arranged in said hollow element and is open to the atmosphere at one end, an outer casing surrounding said hollow element so as to provide a steam jacket therefor which is in constant communication with the interior of the fitting, a valve to control the flow of steam through said steam port, and a pipe extending from said steam jacket to said steam port. 70 75 80 85

2. In a humidifying device the combination with a fitting having a nipple for attaching it to a radiator or the like, and formed with a steam port, of a hollow element secured to said fitting into which said steam port discharges, a hollow silencing body permeable to steam which is arranged in said hollow element and is open to the atmosphere at one end, an outer casing surrounding said hollow element so as to provide a steam jacket therefor which is in constant communication with the interior of the fitting, a valve to control the flow of steam through said steam port, a pipe extending from said steam jacket to said steam port, and a pipe extending through said nipple to said steam port. 90 95 100

3. In a humidifying device the combination with a fitting having a nipple adapted to be attached to a radiator or the like and provided with a steam port, of an inner casing to which said steam port leads, a silencing body permeable to steam arranged in said casing, a discharge pipe from said silencing body, and an outer casing surrounding said inner casing having a head through which said discharge pipe projects, the wall of the outer casing extending beyond said head to provide a space for collecting and evaporating water. 105 110 115

4. A humidifying device comprising a chamber adapted to communicate directly with a source of supply of steam, a silencing element permeable to steam arranged so that the steam from said chamber passes therethrough directly to the atmosphere, a steam jacket surrounding said chamber communicating at one end with said source of supply of steam, and an air drain pipe leading from the other end of said jacket. 120 125

5. A humidifying device comprising a fitting adapted to be attached to a radiator or the like, means associated with said fitting constituting a chamber and a steam jacket surrounding the chamber, a silencing 130

- element permeable to steam arranged so that the steam from the chamber passes therethrough to the atmosphere, and an air pipe which leads from the steam jacket into 5 the interior of said fitting.
6. A humidifying device comprising a fitting adapted to be attached to a radiator or the like, inner and outer tubular casings mounted on said fittings provided with 10 heads and arranged so as to constitute a chamber, a steam jacket surrounding the same and a space above the jacket to collect water of condensation, the outer casing being longer than the inner casing, a 15 tubular silencing body permeable to steam of smaller diameter than the inner casing and arranged within the same, and a discharge pipe leading from said silencing body through the heads of said casings.
- 20 7. A humidifying device comprising a fitting adapted to be attached to a radiator or the like, inner and outer tubular casings mounted on said fitting provided with heads and arranged so as to constitute a chamber 25 and a steam jacket surrounding the same, the outer casing being longer than the inner casing, a tubular silencing body, permeable to steam, of smaller diameter than the inner
- casing and arranged within the same, and a discharge pipe leading from said silencing 30 body through the heads of said casings, said discharge pipe and the wall of the outer casing extending beyond the head of the latter so as to provide an evaporating chamber.
8. In a humidifying device for discharging steam from steam containing means to the atmosphere, the combination of a steam permeable body of silencing material through which steam passes from the containing means to the atmosphere, a structure 40 which completely incloses said body so as to protect the same from contact with the outside atmosphere, said structure being formed with a discharge passageway opening unobstructedly to the atmosphere, and with a steam jacket in communication with said containing means at one end which maintains the steam passing through the device in a heated state, and an air drain pipe 45 which leads from the other end of said steam jacket.
